UNITED STATES PATENT OFFICE

2,584,853

GRAPPLE

Walter H. Elsey, Marble, Ark.

Application November 15, 1946, Serial No. 710,038

1 Claim. (Cl. 294—99)

1
This invention relates to grapples, and has for one of its objects the production of a simple and efficient means for holding the grapple blades firmly in engagement with the jar links so as to avoid shearing off the securing bolts during the process of penetrating hard filling in a well.

A further object of this invention is the production of a simple and efficient means for holding the grapple blades against lateral swing and strain when the blades are secured to the jar links.

Other objects and advantages of the present invention will appear throughout the following specification and claim.

In the drawing:

Figure 1 is a side elevational view of the grapple;

Figure 2 is a side elevational view of the grapple, looking at right angles to Figure 1;

Figure 3 is an enlarged fragmentary perspective view of a portion of the jar link and grapple blades, illustrating the means for anchoring the blades in proper set alignment;

Figure 4 is an enlarged sectional view taken on line 4—4 of Figure 2, the lower bolt being removed;

Figure 5 is a fragmentary perspective view of a portion of the jar link illustrating the blade-anchoring socket;

Figure 6 is an inverted sectional perspective view of the trigger unapplied; and

Figure 7 is a perspective view of the opener tool for the grapple blades.

By referring to the drawing it will be seen that 10 designates the jar links of the grapple of a type somewhat similar to that illustrated in the patent to George W. Russell, #1,721,234, of July 16, 1929.

The jar links comprise an upper section 11 and a lower section 12, which lower section 12 is provided with a depending portion 13. A pair of grapple blades 14 are secured to the depending portion 13 by means of the conventional transversely extending securing bolts 15.

The depending portion 13 is provided with a transversely extending slot 16 located above and in alignment with the apertures 17 which receive the bolts 15. Each grapple blade 14 is provided with an inwardly bent right-angularly anchoring tongue 18 at its upper end which fits snugly within the anchoring slot 16 of the depending portion 13. The slots 16 are formed in opposite sides or faces of the depending portions 13 so as to receive the inwardly extending

2
right-angularly extending anchoring tongues 18 of the opposite grapple blades 14. By means of these tongues 18 which fit within the sockets 16, the grapple blades 14 will be firmly held in alignment with the depending portion 13 and these tongues 18 will resist any strain upon the grapple blades 14 which might otherwise tend to shear off the bolts 15.

In actual practice it has been found that the bolts 15 which are of the conventional type and which are ordinarily used in grapples of the character described very often become sheared off due to the fact that the strain wears upon the bolts and the apertures through which the bolts extend, thereby permitting increasing lateral sway of the grapple blades. From repeated use the bolts often become sheared off and the grapples drop into the well. Where the well is tightly packed with rock and debris it is necessary to penetrate the hard filling of the well by dropping the grapples a considerable distance. The impact has been found to shear off the bolts which hold the blades to the jar links since the blades are only about one-fourth of an inch thick, and it is a difficult task to fish the blades out of the well. By providing the anchoring tongue 18 and the slots 16, it has been found that the shearing of the bolts can be avoided in a great majority of cases.

30 In conjunction with the grapple blades 14 I employ a hinged trigger 19 similar to the trigger in the patent to Russell, above identified, one section 20 being secured to one grapple blade 14 and the other section 21 being secured to the companion grapple blade 14. A cable 22 is connected to the trigger and may be anchored, as at 23.

40 In Figure 7 there is shown a perspective view of a tool which may be used in connection with the present invention for the purpose of operating the grapple blades, and this tool comprises a handle 24 and an offset loop portion 25 which is adapted to fit between the ends of the grapple blades, and a foot-engaging portion 26. This tool is preferably bent from a single one-half inch rod. By placing the right foot on the lower end or portion 26 and placing the loop portion 25 between the blades and lifting upwardly on the handle 24, the blades may be safely and conveniently opened.

50 It will be noted that the inwardly bent tongues 18 carried by the inner end of each blade are inset from the side edges of the depending portion 13, to shield the tongues against contact with the side wall of the well into which the

3

grapple is inserted. It also will be noted that the side edges of the blades contact the depending portion laterally of and below the tongues to resist twisting of the blades relative to the depending portion.

Having described the invention, what is claimed is:

A grapple of the class described comprising a plurality of jar links having parallel side edges, one of said links having a depending portion having flat outer faces, said depending portion having transverse sockets formed on opposite sides thereof in opposed relation and inset from the side edges of the depending portion and in transverse alignment, a grapple blade fitting flat 15 against each opposite face of said depending portion, aligned spaced bolts securing the blades to the depending portion, an inwardly bent anchoring tongue carried by the inner end of each blade and inset from the side edges of said depending 20 portion to shield the tongue against contact with the said wall of the well into which the grapple is inserted, said tongues being in longitudinal alignment with said bolts and in transverse alignment relative to each other and fitting in 25 said sockets on opposite sides of said depending portion to firmly anchor the blades against lat-

4

eral strain and lateral swinging movement relative to the bolts, the tongues and the inner faces of the sockets having abutment relation in a plane at right angles to the tongues, the side edges of the blades contacting the depending portion laterally of and below said tongues to resist twisting of the blades relative to the depending portion, the grapple blades being interchangeable and of substantially duplicate formation to fit flat upon either side of said depending portion and to facilitate the assembling of the grapple irrespective as to the sides upon which the respective grapple blades are fitted.
